Primary Examiner — Marissa J Cash*Assistant Examiner* — Rebecca Tsehayé(74) *Attorney, Agent, or Firm* — IP-PAL Patent US; Klaus Michael Schmid(57) **CLAIM**

The ornamental design for an electronic cigarette, as shown and described.

DESCRIPTION

FIG. 1 is a perspective top front View of an electronic cigarette showing my design;

FIG. 2 is a perspective bottom rear View thereof;

FIG. 3 is a perspective top rear View thereof;

FIG. 4 is a front View thereof;

FIG. 5 is a rear View thereof;

FIG. 6 is a top View thereof;

FIG. 7 is a bottom thereof;

FIG. 8 is a left side View thereof; and,

FIG. 9 is a right side View thereof.

In the drawings, the broken lines represent portions of the electronic cigarette that form no part of the claimed design.
